UNITED STATES PATENT OFFICE.

HENRY JOHN LAWSON, OF LONDON, ENGLAND.

MOTOR-VEHICLE.

SPECIFICATION forming part of Letters Patent No. 654,797, dated July 31, 1900.

Application filed March 28, 1900. Serial No. 10,512. (No model.)

To all whom it may concern:

Be it known that I, HENRY JOHN LAWSON, a subject of the Queen of Great Britain, residing at London, England, have invented 5 certain new and useful Improvements in Motor-Vehicles, of which the following is a specification.

My invention relates to motor-vehicles which are driven or actuated by explosive- 10 motors; and it has for its object to provide rotating parts of the vehicle or motor or of both the motor and vehicle with fan-blades so constructed and arranged that they or either of them will direct a cooling current 15 of air upon the motor or the parts thereof which become highly heated in consequence of the explosion taking place.

My invention is more particularly adapted 20 for use in connection with the type of motor- vehicle for which I obtained United States Letters Patent No. 633,014, under date of September 12, 1899, in which the actuating- motor is mounted directly upon the propelling-wheel and in laterally-disposed relation 25 thereto. It may be sufficient to provide the propelling-wheel alone with the fan-blades; but I prefer an additional fan on the fly-wheel of the motor in order that the parts may be cooling during the periods of temporary stop- 30 page of the propelling-wheel, it being well known that motors of this type are kept in operation during such periods or until a stop of any great length is made, and the fly-wheel may thus be cooling the motor parts during 35 such periods.

My invention will be fully understood upon reference to the accompanying drawing, in which the figure is a vertical axial section of a propelling-wheel provided with a motor 40 and with my improved cooling-fans applied thereto.

1 represents the propelling-wheel; 2, the motor-axle concentrically arranged therein; 3, a motor for driving said axle, and 4 a fly-wheel 45 forming part of the motor mechanism. These parts may of course vary according to circumstances.

I have selected for purposes of illustration a machine constructed in accordance with my 50 Letters Patent No. 633,014, hereinbefore referred to.

To the spokes 5 of the wheel 1 I apply suit-

able fan-blades 6, which are so set that when the wheel is in rotation a strong current of air will be directed by said blades in a direction transverse of the wheel and through the motor 3. This will be true independently of the wind or natural currents of air or any relative movement of the air resulting from the movement of the vehicle. Coöperating 55 with the fan-blades 6 is an auxiliary fan 7, which may be mounted in any suitable manner upon the fly-wheel 4. I prefer to have this fan secured peripherally upon the fly-wheel in substantially the same plane as the latter. These details, however, may be varied without departing from the spirit of my invention. This auxiliary fan 7 coöperates with the fan 6 while the vehicle is in motion, and particularly with the inner portion of the fan 6, where the blades are necessarily narrow and the motion considerably reduced to send a strong current of air among the parts of the motor. Moreover, when the wheel 1 is at rest and the fly-wheel 4 continues rotation fan 7 will then send an independent current of air through the motor and continue the cooling effect upon the motor. It will be understood that the parts of the blade 6 that overlap in a horizontal direction the blades 80 of fan 7 will be narrow and will not fill the space between the spokes, and hence the current set up by the fan 7 when the wheel 1 is at rest will have its effect upon the motor located on the opposite side of the wheel. 85

Having thus described my invention, the following is what I claim as new therein and desire to secure by Letters Patent:

1. In combination with a motor-vehicle having a supporting and propelling ground-wheel, a motor mounted laterally to and driving said supporting and propelling ground-wheel, and fan-blades mounted upon said supporting and propelling ground-wheel sending a current transversely through the wheel 90 and motor.

2. In combination with a motor-vehicle having a motor supporting and propelling ground-wheel, a motor laterally disposed thereto and driving the same, a fly-wheel on the shaft of the motor, and a fan located upon the fly-wheel sending a current of air transversely through the motor, for the purpose set forth.

3. In combination with a motor-vehicle having a supporting and propelling ground-wheel, a motor and its fly-wheel, located on opposite sides of the supporting and propelling wheel, and a fan on the fly-wheel sending a current transversely through the vehicle-wheel and motor, for the purpose set forth.
5. In combination with a supporting and propelling ground-wheel of a vehicle, a shaft 10 extending axially through and having driving connection with said ground-wheel, a motor and its fly-wheel connected to opposite ends of said shaft, and a fan on said fly-wheel

sending a current of air transversely through the ground-wheel and motor.

5. In combination with a motor-vehicle having a motor and a fly-wheel laterally disposed with relation to the propelling-wheel of the vehicle, a fan upon the propelling-wheel, and an auxiliary fan upon the fly-wheel co-operating with the same; substantially in the manner and for the purpose set forth.

HENRY JOHN LAWSON.
